DESIGN FOR A HAT TRIMMING OR SIMILAR ARTICLE

Abraham Gerstenzang, New York, N. Y.

Application October 7, 1942, Serial No. 108,459

Term of patent 3½ years

To all whom it may concern:

Be it known that I, Abraham Gerstenzang, a citizen of the United States, residing in New York city, in the county of New York and State of New York, have invented a new, original, and ornamental Design for a Hat Trimming or Similar Article, of which the following is a specification, reference being had to the accompanying drawing, forming part thereof.

Fig. 1 is a front elevational view of a hat trimming or similar article showing my new design, and

Fig. 2 is an enlarged fragmentary view of Fig. 1.

The rear view of Fig. 1 is the same.

I claim:

The ornamental design for a hat trimming or similar article, substantially as shown and described.

ABRAHAM GERSTENZANG.
